DESTRUCTIBLE HOLLOW FORM

Lillian L. Greneker, New York, N. Y.

Application October 28, 1943, Serial No. 507,989

12 Claims. (Cl. 18—45)

This invention relates to destructible forms such as those used in the manufacture of fuel tanks and cells or other articles made of rubber or other material. The fuel tank or cell or other article is made on the form, after which the form is destroyed and removed. Such forms must be cheap to manufacture, light, strong and rigid, accurate as to shape and dimensions, and not subject to change of shape or dimensions under conditions such as heat and moisture to which they may be subjected in use. Such forms also must be capable of being readily destroyed and removed from the fuel tank or cell or article which may be made on them, even though the opening in the article through which the pieces of the form must be removed is comparatively small. The present invention is not concerned with the particular shape of the form, but merely with its construction, since of course the constructions hereinafter described may be used in forms having an infinite variety of shapes and sizes.

The general object of the present invention is to provide improved form constructions which satisfy particularly well the above mentioned requirements. To these ends, the invention is characterized by the use of flexible sheet material, such as heavy paper made of wood-pulp, which is bonded to the inner sides of the molded frangible material, such as plaster of Paris, of which the forms are made in a mold to the exact shape and size desired. Wherever the term "paper" is hereinafter used it is intended to include all equivalent sheet materials. Such paper may be used in various ways, depending upon the size and shape of the walls of the form which are to be reinforced and strengthened. Also, various kinds of paper may be advantageously employed, for example, plain paper, or pressed paper having surfaces other than plane surfaces, for example, corrugated or dimpled surfaces. In practice, the paper is preferably wiped into liquid plaster of Paris or other material used in molding the form, and is then applied during the making of the form to the inner wall of that portion of the form where reinforcing is desired, with the result that the paper is bonded to the inside of the wall of the form when the plaster sets. In some cases, the paper may be applied to the inner wall of the form in fairly large pieces or sheets; but I have found that it is often advantageous to tear the paper into pieces having an area of only a few inches and then to apply these pieces to the inner wall of the form in slightly overlapping relation bonded to one another; both because

that way of applying the paper facilitates application of the paper to rounded or curved surfaces, and also because it permits the escape of air from beneath the paper and substantially eliminates air pockets between the paper and the plaster in the wall of the form. In some cases, it may be desirable to increase the reinforcing effect by applying two or more layers of pieces of paper bonded together and to the inside of the plaster in the wall of the form.

Where it is desirable to reinforce wall areas of considerable size, the paper may be folded or otherwise arranged before or at the time of applying it to the inside of the wall of the form, so that a reinforcing effect is obtained by fins composed of paper and plaster bonded together and bonded to the inside of the wall of the form.

Examples of these various ways of reinforcing the walls of a form are hereinafter described and 20 are shown in the drawings. It will be apparent that destructible forms made according to the present invention are composed entirely of frangible material such as plaster of Paris and paper; and that destruction of the form, after it 25 has served its purpose, may be facilitated by the absorption of moisture by the paper, whether such moisture results from the use of the form in making fuel tanks or cells or other articles, or results from injection of moisture into the form.

30 The invention will be understood from the following description taken in connection with the accompanying drawings in which Fig. 1 is a fragmentary view of the inside of the wall of a form having reinforcing paper applied thereto in overlapping pieces; Fig. 2 is a section on the lines 2—2 of Fig. 1; Fig. 3 is a fragmentary view of the concave inside of a form wall reinforced by corrugated paper bonded thereto; Fig. 4 is a section on the line 4—4 of Fig. 3; Fig. 5 is a fragmentary view of the inside of a rounded form wall reinforced by pressed dimpled paper; Fig. 6 is a section on the line 6—6 of Fig. 5; Fig. 7 is a fragmentary perspective view partly in section, showing a reinforcing fin of paper and plaster bonded together and bonded directly to a form wall; Fig. 8 is a sectional view showing a reinforcing fin bonded to reinforcing paper which is bonded to the inside of a form wall; Fig. 9 shows in elevation how the folded paper used in making

50 a fin may be cut to facilitate application of the fin to the convex surface of a form wall; Fig. 10 shows in elevation how the folded paper may be cut to facilitate its application to a concave surface of a form wall; and Fig. 11 is a plan view showing how the folded paper may be cut to

facilitate the making of a bent fin. It will, of course, be understood that folded paper with plaster may be used in other ways in the forming of reinforcing fins, and that those herein described are merely illustrative of that aspect of the invention.

Referring to Figs. 1 and 2, a section of the plaster form wall is shown at 15 as having a smooth outside molded surface 16, and an inside surface 17 to which torn pieces of paper 18, 19, 20, 21, etc., are applied preferably in overlapping relation. These pieces of paper are wiped into or otherwise smeared with liquid plaster and are then applied to the inner side of the form wall while the latter is still wet. Thus the pieces of paper are bonded to the plaster of the wall of the form, and when the plaster has set the paper serves to reinforce the wall of the form which can be made comparatively thin for that reason. In Figs. 1 and 2 the pieces of paper are shown applied in one layer to the wall of the form; but it will be understood that two or more layers bonded together by plaster may be employed, as may be necessary to provide proper reinforcing.

Another type of reinforcing is shown in Figs. 3 and 4, in which a fragment of a wall of a form is shown at 24, with its smooth outer molded surface represented at 25. To the inner surface of the plaster wall 24, a piece of corrugated paper 26 is bonded by being first smeared on one side with wet plaster and then pressed against the wet plaster of the wall 24. In this case, as in the construction shown in Figs. 1 and 2, the corrugated paper may be torn or cut into comparatively small pieces and applied in overlapping relation, in order to eliminate air pockets between the paper 26 and the plaster wall 24.

Figs. 5 and 6 represent a construction similar to that represented in Figs. 3 and 4, except that pressed dimpled paper 28 is applied to the inside surface of a rounded form wall 29, the outside smooth molded surface of which is indicated at 30. As described in connection with Figs. 1 and 2, the dimpled paper 28 of course may be applied in overlapping pieces. Such pressed paper lends itself particularly well to the reinforcing of rounded form walls.

Fig. 7 shows a section of form wall 34 reinforced by a fin bonded to said wall. As will be clear from Fig. 7, this reinforcing fin comprises a piece of paper which has been wiped into or otherwise smeared with wet plaster on one side, folded into the shape shown, and then applied to the inner surface of the plaster form wall 34 when the latter is in a wet condition, thereby producing bonding of the composite paper-and-plaster fin to the form wall. As will be apparent, the paper is so folded that its cross-section resembles the letter T (inverted as shown in Fig. 7) with adjacent folds 36 and 37 and wings 38 and 39. Creasing of the paper will generally be found to be desirable before it is smeared with plaster; and enough plaster should be smeared on to produce a thin layer between the adjacent folds 36 and 37 of the paper, and to provide for bonding of the wings 38 and 39 to the plaster of the form wall 34.

Fig. 8 shows a structure which is similar to Fig. 7, except that the inner surface of the form wall 40 is reinforced with pieces of paper 41 (in the manner described in connection with Figs. 1 and 2), before the reinforcing fin is applied. Thus, with the construction shown in Fig. 8, the form wall 40 is reinforced both by the paper 41 bonded to its inner surface and by the composite paper-

and-plaster fin which is bonded to the first mentioned paper.

Destructible forms may be of a great variety of shapes, and it may be desirable to apply reinforcing fins to convex surfaces, to concave surfaces, and in a bent as well as a straight line. As has been hereinbefore mentioned, it is convenient to fold the paper used in the fins in advance of its use; and when such paper is to be used in making curved or bent fins it should be cut in one or more of the ways illustrated in Figs. 9, 10 and 11. Fig. 9 shows in elevation how the adjacent folds of a fin paper may be cut at 45 down to the wings to facilitate the use of the paper in the making of a fin applied to a convex form wall 46. Fig. 10 shows in elevation how the adjacent folds of the fin paper may be cut to form notches 48, to facilitate use of the paper in the making of a fin applied to a concave form wall 49. Fig. 11 shows in elevation how the wings 38' and 39' of a fin paper may be cut at 50 and notched at 51 to facilitate the making of a bent fin. It will be obvious that by cutting the fin paper in the manner shown in Figs. 9, 10 and 11 the making of curved and bent composite fins of paper-and-plaster is facilitated. After such fins have been applied to the inside of a form wall, and the plaster has set, the fins provide a very rigid reinforcement of the form wall. Therefore, the use of such fins makes possible the making of comparatively thin form walls which are strong and rigid, even though such walls may be of considerable length and width. Thus the making of a satisfactory, light form is facilitated; and the materials used to make the form are readily de-structible after it has served its purpose.

What is claimed is:

1. In a destructible hollow form which in outside shape and size conforms to the space within a hollow article which is to be made on said form, a wall composed of molded frangible material reinforced and strengthened plaster with paper bonded to the inside of the molded frangible material of the wall.
2. In a destructible hollow form which in outside shape and size conforms to the space within a hollow article which is to be made on said form, a wall composed of molded frangible material reinforced with pieces of paper arranged in overlapping relation and bonded together and to the inside of the molded frangible material of the wall.
3. In a destructible hollow form which in outside shape and size conforms to the space within a hollow article which is to be made on said form, a wall composed of molded frangible material reinforced with a plurality of layers of pieces of paper arranged in overlapping relation and bonded together and to the inside of the molded frangible material of the wall.
4. In a destructible hollow form which in outside shape and size conforms to the space within a hollow article which is to be made on said form, a wall composed of molded frangible material reinforced with pressed paper having surfaces other than plane surfaces bonded to the inside of the molded frangible material of the wall.
5. In a destructible hollow form which in outside shape and size conforms to the space within a hollow article which is to be made on said form, a wall composed of molded frangible material reinforced by a fin composed of paper and frangible material bonded together and

bonded to the inside of the molded frangible material of the wall.

6. In a destructible hollow form which in outside shape and size conforms to the space within a hollow article which is to be made on said form, a wall composed of molded frangible material reinforced by a fin composed of folded paper enclosing frangible material bonded to the paper and to the inside of the molded frangible material of the wall.

7. In a destructible hollow form which in outside shape and size conforms to the space within a hollow article which is to be made on said form, a wall composed of molded frangible material reinforced by paper bonded to the inside of said wall and also reinforced by a fin composed of paper and frangible material bonded together and bonded to the first mentioned paper.

8. In a destructible hollow form which in outside shape and size conforms to the space within a hollow article which is to be made on said form, a wall composed of molded frangible material reinforced by paper bonded to the inside of said wall and also reinforced by a fin composed of folded paper enclosing frangible material bonded to the folded paper and to the first mentioned paper.

9. In a destructible hollow form which in outside shape and size conforms to the space within a hollow article which is to be made on said form, a wall reinforced by a fin composed of paper folded so that its transverse cross-section resembles the letter T and also composed of frangible material enclosed within the paper and bonded thereto and to the inside of the wall.

10. In a destructible hollow form which in outside shape and size conforms to the space within a hollow article which is to be made on said form, a wall reinforced by a fin composed of paper folded so that it has adjacent folds and wings, said fin being also composed of frangible material enclosed within the adjacent folds of the paper and bonded thereto and to the wings of the paper and to the inside of the wall.

11. In a destructible hollow form which in outside shape and size conforms to the space within a hollow article which is to be made on said form, a curved wall reinforced by a curved fin composed of paper folded so that it has adjacent folds and wings, the adjacent folds of said paper being cut and the folded paper being bent so as to conform generally to the curved wall of the form, said fin being also composed of frangible material enclosed within the adjacent folds of the paper and bonded thereto and to the wings of the paper and to the inside of the wall.

12. In a destructible hollow form which in outside shape and size conforms to the space within a hollow article which is to be made on said form, a wall reinforced by a bent fin composed of paper folded so that it has adjacent folds and wings, the wings of the folded paper being cut and the adjacent folds of said paper being bent at the point of cutting, said fin being also composed of frangible material enclosed within the adjacent folds of the paper and bonded thereto and to the wings of the folded paper and to the inside of the wall.

LILLIAN L. GRENEKER.

CERTIFICATE OF CORRECTION.

Patent No. 2,369,892.

February 20, 1945.

LILLIAN L. GRENEKER.

It is hereby certified that error appears in the printed specification of the above numbered patent requiring correction as follows: Page 2, second column, line 43, claim 1, strike out "plaster" and insert the same before "material" in line 45, same claim; and that the said Letters Patent should be read with this correction therein that the same may conform to the record of the case in the Patent Office.

Signed and sealed this 12th day of June, A. D. 1945.

Leslie Frazer
